APPARATUS FOR DISCHARGING OBJECTS

Edgar William Brandt, Paris, France, assignor to
 Sageb, Société Anonyme de Gestion et d'Exploitation de Brevets, Fribourg, Switzerland, a
 corporation of Switzerland

Application June 22, 1938, Serial No. 215,283
 In France June 25, 1937

9 Claims. (Cl. 89—1.5)

This invention relates to an apparatus for discharging into the atmosphere various objects such as aerial mines or other elements of an aerial net, aircraft bombs, smoke-producing charges, parcels of provisions or medicaments and generally any charges which it is desired to release in succession from an aircraft or elevated point.

The majority of apparatus of this type at present in use, and particularly bomb releasing apparatus, only permit the discharge of such objects at a relatively slow rate. However for certain applications, and especially for the purpose of producing a sufficiently dense serial barrage with the aid of isolated mines, it is necessary that the objects should be discharged at a very rapid rate.

The apparatus of the present invention is of the type possessing compartments in which the objects to be discharged are disposed in a row, one end of which faces an outlet door.

According to the present invention each row of objects is surrounded by a flexible member: cable, link, band, belt or like member disposed in the form of a loop open near the door, one of its ends, which passes along one side of the row, being attached to a fixed point of the apparatus, while the other end, which runs along the other side of the row, is subjected to traction at the moment of discharge, in order to apply to the row of objects a push which drives them through the door.

The flexible band may be pulled either by hand or with the aid of any mechanical means which, when the apparatus is mounted on an aircraft, may be controlled by the engine.

This arrangement enables the objects to be discharged at a much quicker rate than if they were simply allowed to escape by gravity, as in ordinary bomb-releasing apparatus.

According to another feature of the invention, the discharge doors of each compartment are so disposed as to be locked by the objects located in an adjoining compartment and to be capable of opening only when the latter is completely emptied.

A further feature of the invention is that the same draw-band surrounds each row of objects housed in the successive compartments, and is carried by the various doors in such a manner as to apply thereon a pressure which opens them in turn as soon as the preceding compartment is emptied of its contents.

This arrangement contributes greatly towards increasing the rapidity of discharge, since the rows of objects can thus be discharged from the apparatus without a break.

The door of the compartment of the apparatus which opens first is locked by a special bolt until the moment of discharge.

The apparatus of the present invention is further characterised by the provision in each compartment of resilient stops adapted to retain the objects of each row inside the compartment when no traction is applied to the band, said stops being so designed as to yield under the push of the objects when the band drives the latter towards the discharge door. By virtue of this construction the distribution of a row of objects in course of discharge can be stopped by merely ceasing to pull the band.

According to a modification of the invention, the apparatus comprises a certain number of horizontal compartments closed by rocking doors or flaps, said doors being locked by latches held in the operative position by a belt, band, link or the like surrounding the rows of objects housed in said compartments, the unwinding of the band during the discharge operation releasing the latches, which rock and permit the opening of the doors under the pressure of the rows of objects driven outwards by the traction applied to the band. This arrangement enables objects to be discharged horizontally.

Other features and advantages of the invention will become apparent from the following description taken in conjunction with the accompanying drawings which illustrate diagrammatically and by way of example various embodiments thereof, and in which—

Fig. 1 is an elevation of one embodiment;

Fig. 2 is a perspective view of a support member for a row of objects to be discharged;

Fig. 3 is an elevation of two compartments of the apparatus of Fig. 1, showing the parts in the position they occupy during the discharge of the objects;

Fig. 4 is a side elevation of the apparatus shown in Fig. 1; and

Fig. 5 is a diagrammatic view of an embodiment adapted to discharge objects horizontally.

The apparatus shown in Figs. 1 to 4, comprises a fixed frame, the vertical longitudinal members 1 and horizontal longitudinal members 2 of which bound a certain number of compartments 3, 4, 5 in which are housed the rows of objects 6 to be discharged. The latter are shown in the drawings in the form of cylindrical bodies. The rows of objects rest on forks 7, 8, 9 integral with movable frames 10, 11 and 12 respectively, adapted to rock around pins 13, 14, 15, respectively. A flexible member: cable, link, tape or

band 16 is attached at one of its ends 17 to the frame and surrounds in succession each row of objects 6, passing over pulleys 18, 19, 20 carried by the ends of the forks 7, 8, 9 respectively. On leaving the last compartment on the right (3, Fig. 1) the cable or band 16 passes over pulleys 21, 22 on a bolt bearing against the fork 7 on the frame 10, in order to lock it in the closed position.

The bolt 21, 22 is locked in the position shown 10 in Fig. 1, for example by a detachable pin 22a.

The forks 7, 8, 9 of each frame act as discharge doors for the various compartments 3, 4, 5 respectively, of the apparatus.

The free end of the cable or band 16 may be 15 wound on a reel or winch 55 adapted to be operated by hand or by a motor, in order to apply a pull on the cable or band 16.

The width of the forks 7, 8, 9 is substantially equal to that of each compartment 3, 4, 5, so 20 that, in the position of rest, the end of each fork bears against the movable frame of the adjoining fork and locks it in closed position.

One or more resilient stops 25 (Fig. 3) may be 25 provided to balance the weight of the objects to be discharged and hold them in position in each compartment 3, 4, 5.

Holes 26 (Fig. 4) may advantageously be provided in the parts of the apparatus in order to render them lighter.

The apparatus operates as follows:

After the objects 6 to be discharged have been introduced through the openings 30 into the various compartments 3, 4, 5, of the apparatus and the band 16 has been wound round them, as shown in the drawing, all that is necessary for the discharge of the objects, is to remove the pin 22a or other locking member for the bolt 21, 22 and to apply a pull on the band 16. The bolt 21, 22 turns in the direction of the arrow 40 F1 and the cable band 16 rocks the fork-carrier frame 10 to the right around the pin 13, thus opening the door of the compartment 3. The band 16 pushes the objects 6 downwards, overcoming the resistance of the resilient stops 25, 45 and drives them out of the compartment.

As soon as the first compartment 3 is emptied of its contents, the fork or door 8, which was held until that moment in the closed position by the objects 6 in the adjoining compartment 4, is 50 opened by the band 16, which rocks the fork-carrier frame 11 around its pin 14. The objects 6 of the compartment 4 are then driven out like those of the preceding compartment 3, and so on.

In the embodiment shown in Fig. 5, the objects 6 are disposed in horizontal rows in the superposed compartments 31, 32, 33.

The latter are closed by doors 35, 36, 37 respectively, which are articulated on horizontal hinges 39, 40. These doors are locked by latches 44, 45 adapted to pivot around pins 47, 48, 49 and held in the position shown by a band or belt 16 mounted around the rows of objects 6 in the same manner as described with reference to Figs. 1 to 4. The band 16 is guided by pulleys 50, 51, 43 and by a turnpike 52, the arms 53 of which extend into the mouth of the hopper 54 in order to hold the objects within the apparatus as long as the turnpike is held against turning. The band 16 is led to a winch 55 through which it may be pulled by turning the handle 56 of the winch in the direction of the arrow. The bolt 35 of the first compartment 31

is locked by special locking device similar to that shown in Fig. 1.

It is sufficient to apply traction to the flexing band with the aid of the reel 55 to drive out the rows of objects contained in the various compartments horizontally and at a rapid rate.

Instead of using a single cable or similar flexible member to control the release of the objects, a plurality thereof disposed at a distance from one another and engaging, if necessary, in guide grooves provided on the periphery of the objects—may naturally also be provided.

I claim:

1. An apparatus for discharging objects, formed with successive compartments and comprising a fixed frame, doors in said fixed frame for the respective compartments, means to pivotally mount said doors to said fixed frame, the objects to be discharged being stacked in rows and resting on said doors, means to open said doors when the objects are to be discharged, a flexible band member having one end attached to the fixed frame and passing successively about each row of objects, first encircling said objects at the end of the row remote from the door, then passing about a succeeding row, thereby forming loops open near said doors, and the other end of said flexible band being free for pulling engagement whereby a pull on said free end will exert a pressure on the encircled end of the rows to discharge the objects from the compartments.

2. An apparatus for discharging objects formed with successive compartments and comprising a fixed frame, doors in said fixed frame for the respective compartments, means to pivotally mount said doors to said fixed frame, the objects to be discharged being stacked in rows and resting on said doors, means to open said doors when the objects are to be discharged, means on said doors to prevent each of the doors, except that of the first compartment, to be opened as long as the preceding compartment is not emptied of its objects, a flexible band member having one end attached to said frame, the other end being free for pulling engagement whereby a pull on said free end will exert a pressure on the encircled end of the rows to discharge the objects from the compartments.

3. An apparatus for discharging objects, formed with successive compartments and comprising a fixed frame, doors in said fixed frame for the respective compartments, means to pivotally mount said doors to said fixed frame, the objects to be discharged being stacked in rows and resting on said doors, a flexible band member having one end attached to the fixed frame and passing successively about each row of objects, first encircling said objects at the end of the row remote from the door, then passing about and engaging the door before proceeding about a succeeding row, thereby forming loops open near said doors, and the other end of said flexible band being free for pulling engagement whereby a pull on said free end will first exert a force on a door and cause it to rock on said pivot means and to move out of the path of said row of objects in the respective compartment, said flexible band then exerting a pressure on the encircled end of the row to discharge the objects from the compartment and thereby allow the door of the adjacent compartment to rock into the space vacated by the discharged objects.

4. An apparatus for discharging objects,

formed with successive compartments and comprising a fixed frame, doors on said frame for the respective compartments, means to pivotally mount said doors to said fixed frame, means to lock, until the moment of discharge, the door of that one of the compartments which opens first, the objects to be discharged being stacked in rows and resting on said doors, a flexible band member having one end attached to the fixed frame and passing successively about each row of objects, first encircling said objects at the end of the row remote from the door, then passing about and engaging the door before proceeding about a succeeding row, thereby forming loops open near said doors, and the other end of said flexible band being free for pulling engagement whereby a pull on said free end will first exert a force on a door and cause it to rock on said pivot means and to move out of the path of said row of objects in the respective compartment, 10 said flexible band then exerting a pressure on the encircled end of the row to discharge the objects from the compartment and thereby allow the door of the adjacent compartment to rock into the space vacated by the discharged objects.

5. An apparatus for discharging objects comprising a fixed frame, rockable frame members each comprising a relatively long portion having a fork portion at one end extending laterally therefrom, means to pivotally mount the other end of said rockable members to said fixed frame, said rockable frame members cooperating with the fixed frame to form successive compartments, said fork portions of said rockable frame members constituting doors for the respective compartments, the objects to be discharged being stacked in rows and resting on said doors, a flexible band member having one end attached to the fixed frame and passing successively about each row of objects, first encircling said objects at the end of the row remote from the door, then passing about and engaging the fork portion of said rockable frame before proceeding about a succeeding row, thereby forming loops open near said doors, and the other end of said flexible band being free for pulling engagement whereby a pull on said free end will first exert a force on a fork portion and cause said respective rockable frame member to rock on said pivot means and said door to move out of the path of said row of objects in the respective compartment, said flexible band then exerting a pressure on the encircled end of the row to discharge the objects from the compartment and thereby allow the adjacent rocking frame to rock into the space vacated by the discharged objects.

6. An apparatus for discharging objects comprising a fixed frame, rockable frame members each comprising a relatively long portion having a fork portion at one end extending laterally therefrom, means to pivotally mount the other end of said rockable members to said fixed frame to form successive compartments, said fork portions of said rockable frame members constituting doors for the respective compartments, the objects to be discharged being stacked in rows and resting on said doors, resilient stops in said compartments to sustain the objects in each row, a flexible band member having one end attached to the fixed frame and passing successively about each row of objects, first encircling said objects at the end of the row remote from the door, then passing about and engaging the fork portion of said rockable frame before proceeding about a succeeding row, thereby forming loops open near

5 said doors, and the other end of said flexible band being free for pulling engagement whereby a pull on said free end will first exert a force on a fork portion and cause said respective rockable frame member to rock on said pivot means and said door to move out of the path of said row of objects in the respective compartment, said flexible band then exerting a pressure on the encircled end of the row to cause said resilient stops to yield and to discharge the objects from the compartment and thereby allow the adjacent rocking frame to rock into the space vacated by the discharged objects.

10 7. An apparatus for discharging objects, formed with successive compartments and comprising a fixed frame, doors in said fixed frame for the respective compartments, means to pivotally mount said doors to said fixed frame, the objects to be discharged being stacked in rows and resting on said doors, a flexible band member having one end attached to the fixed frame and passing successively about each row of objects, first encircling said objects at the end of the row remote from the door, then passing about 15 and engaging the door before proceeding about a succeeding row, thereby forming loops open near said doors, and the other end of said flexible band being free for pulling engagement whereby a pull on said free end will first exert a force on a door and cause it to rock on said pivot means and to move out of the path of said row of objects in the respective compartment, said flexible band then exerting a pressure on the encircled end of the row to discharge the objects from the compartment and thereby allow the door of the adjacent compartment to rock into the space vacated by the discharged objects and guiding pulleys mounted in the apparatus to guide said flexible band.

20 8. An apparatus for discharging objects, formed with successive compartments and comprising a fixed frame, doors in said fixed frame, for the respective compartments, means to pivotally mount said doors to said fixed frame, latches to lock said doors, the objects to be discharged being disposed in rows ending facing said doors, a flexible band member attached to the fixed frame and passing successively about each row of objects, first encircling said objects at the end 25 of the row remote from the door, then passing about and engaging said latches before proceeding about a succeeding row, thereby forming loops open near said doors, and the other end of the flexible band being free for pulling engagement whereby a pull on said free end will first exert a force on said latches and move them into 30 inoperative position, said flexible band then exerting a pressure on the encircled end of the row to discharge the objects from the compartment.

35 9. An apparatus for discharging objects from an aircraft comprising a fixed frame, rockable frame members each comprising a relatively long portion having a fork portion at one end extending laterally therefrom, means to pivotally mount the other end of said rockable member to said fixed frame, said rockable frame members cooperating with the fixed frame to form successive compartments, said fork portion of said rockable frame members constituting doors for the respective compartments, the objects to be discharged being stacked in rows and resting on said doors, a flexible band member having one end attached to the fixed frame and passing successively about each row of objects, first encircling said objects 40 at the end of the row remote from the door, then

4
passing about and engaging the fork portion of said rockable frame member before proceeding about a succeeding row, thereby forming loops open near said doors, and the other end of said flexible band being free for pulling engagement whereby a pull on said free end will first exert a force on a fork portion and cause said respective rockable frame member to rock on said pivot

means and said door to move out of the path of said row of objects in the respective compartment, said flexible band then exerting a pressure on the encircled end of the row to discharge the objects from the compartment and thereby allow the adjacent rocking frame to rock into the space vacated by the discharged objects.

5
EDGAR WILLIAM BRANDT.
